PIPE WRENCH

Clarence A. Huntley, Minatare, Nebr.

Application August 14, 1936, Serial No. 96,084

2 Claims. (Cl. 81—128)

My invention relates to improvements in pipe wrenches and is designed with the particular purpose in view of providing a quick-acting practical pipe wrench of few parts and in which the gripping of a pipe, or other article, is effected by movement of the handle of the wrench around the pipe, or article, in the direction in which the latter is to be turned.

Another object is to provide a pipe wrench of the character and for the purpose above set forth, adapted for setting to vary the gripping action under such movement of the handle.

Still another object is to provide a pipe wrench adapted for effecting a maximum and a limited degree of gripping action, respectively, and settable for predetermining the degree of said gripping action to be effected in connection with different sizes of pipes.

Other objects are to provide a wrench of the character and for the purpose above set forth which is easy to manipulate, will positively not slip, is strong and durable, and which may be manufactured at comparatively low cost.

Other and subordinate objects, together with the precise nature of my improvements, will become apparent when the following description and claims are read with reference to the drawing accompanying and forming part of this specification.

30 In said drawing:

Figure 1 is a view in side elevation of a pipe wrench embodying my improvements, the parts being shown in normal position.

Figure 2 is a similar view, partly in section, illustrating the operation of the wrench parts.

Figure 3 is a view in rear elevation.

Figure 4 is a view in transverse section taken on the line 4—4 of Figure 1 looking in the direction indicated by the arrows.

40 Figure 5 is a view in longitudinal section taken on the line 5—5 of Figure 1 looking in the direction indicated by the arrows, and

Figure 6 is a view in perspective of a pawl for effecting different settings of the wrench.

45 Reference being had to the drawing by numerals, the wrench of my invention comprises outer and inner jaw members 1 and 2, respectively, relatively movable, a carriage 3 for the outer jaw member, and a handle 4.

50 The outer jaw member 1 comprises the usual toothed head 5 and the right-angularly extending shank part 6. The carriage 3 comprises a U-shaped yoke member 7 straddling the shank part 6 for sliding movement on the back edge thereof and including spaced-apart side arms 8 extend-

ing forwardly of the shank part 6 opposite the head 5. The inner jaw member 2 comprises a toothed front end 9 for co-operation with the head part 1, a rear extension 10 designed to extend beyond the carriage 3, and a straight rear edge 11 opposed to the outer edge of the shank part 6. The inner jaw member 2 is mounted in the carriage 3 between the arms 8 for both pivotal and end-wise sliding movement therein with its toothed end 9 opposed to the head part of the outer jaw member 1 and its edge 11 opposed to the shank part 6. The mounting of said jaw member 2 comprises a pin 12 passing through a longitudinally extending slot 13 in said jaw member 2 and having its opposite ends riveted in the arms 8. The slot 13 is designed to permit a limited degree of end-wise movement of the jaw member 2 in the carriage 3 and a limited degree of lateral play of said member in said carriage 3, for a purpose presently clear.

20 The handle 4 comprises a hand-grip part 14 and a bifurcated head part 15 comprising side plates 16 adapted to straddle the carriage 3, the shank part 6 and the inner jaw member 2. The plates 16 are provided with rear ear-like edge extensions 17, by means of which said head and handle are pivotally mounted on the back of the carriage 3 to swing out of a normal position of alignment with the shank part 6 forwardly of the latter. As shown, the pivotal mounting comprises a pair of laterally spaced lugs 18 on the rear edge of the carriage 3 and a pivot bolt 19 passing through said extensions and lugs.

25 The jaw members 1 and 2 are relatively settable into approximate gripping position by sliding the carriage 3 and the shank part 6 relatively into different fixed positions established by means of ratchet teeth 20 formed on the rear edge of the shank part 6 and a pawl 21 pivoting on the before-mentioned bolt 19 between the lugs 18, to swing 30 into and out of engagement with said teeth. The pawl 21 comprises a thumb piece 22 for manipulation thereof and is urged into engaging position by means of a leaf spring 23 suitably secured to the carriage 3 and bearing outwardly against said thumb piece 22.

35 The inner jaw member 2 is movable toward and from the outer jaw member 1 independently of the carriage 3 under movement of the handle 4 by a camming connection between said member 2 and the head part 15 of said handle and comprising the following:

40 The head part 15 is provided internally thereof with opposed pairs of arcuate cam members 24 on opposite plates 16, respectively, forming 45

arcuate opposed grooves 25 between the members of said pairs disposed eccentrically of the pivotal point of connection of the handle 4 to the carriage 3. The inner jaw member 2 is formed with a pair of arcuate ribs, or tongues, 26, upon opposite sides of the extension 10 thereof, respectively, said ribs being concentric to the grooves 25 and slidingly fitting therein. The described camming connection is such that upon forward movement of the handle 4 the inner jaw member 2 is moved toward the outer jaw member 1 to grip a pipe therebetween in any of the set positions of said members. The before-mentioned relation of the slot 13 and pin 12 provides for limited movement of the jaw member 2 in the carriage 3 and also for limitation of movement of the handle 4 into and from a position parallel with the shank part 6. The before-mentioned degree of lateral play of the jaw member 2 provides for movement thereof compensating for the throw of said member under the action of the described camming connection.

In the use of the described wrench, the pawl 21 is disengaged from the teeth 20 and the carriage 3 and the shank part 6 adjusted relatively to position the said jaws closely adjacent to the article to be gripped and with the handle 4 swung to the limit of its movement in a rearward direction as determined by engagement of the pin 12 with one end of the slot 13. In this position of the parts the carriage 3 is locked to the shank part 6 by means of the pawl 21 and the teeth 20. Under forward turning movement of the handle 4 about the bolt 19, the described camming connections 24, 25 and 26 force the inner jaw member 2 against the article into gripping co-operation with the jaw member 1, such movement of the jaw member 2 being independent, as will be clear. The degree of such independent movement of the jaw member 2 under turning movement of the handle 4 in this direction may be varied, and consequently the degree of gripping action of said jaws, by setting the carriage 3 and parts connected therewith on the shank part 6, or vice-versa, to different positions.

The foregoing detailed description of my improved wrench will, it is believed, suffice to impart a clear understanding thereof.

It is to be understood, however, that the present disclosure is illustrative of a preferred embodiment of my invention only, and that right is herein reserved to modifications of details described falling within the scope of the claims appended hereto.

What I claim is:

1. A wrench comprising a stationary jaw, a guide carried by said jaw, a carriage slidably engaging said guide and having spaced apart extensions, means to detachably secure said carriage to said guide, a movable jaw loosely engaging between said extensions and having an elongated opening parallel with said guide, a pin extending through said opening and fixed to said extensions, a handle, spaced apart cam members secured to said handle and engaging on opposite sides of said carriage, means pivotally securing said cam members to said carriage, a pair of spaced apart arcuate ribs carried by each cam member, and a pair of arcuate ribs carried by said movable jaw one on each side thereof eccentric to said pivot means and engaging between said ribs.

2. A wrench comprising a stationary jaw, a guide carried by said jaw, a carriage slidably engaging said guide and having spaced apart extensions, means to detachably secure said carriage to said guide, said means including teeth carried by said guide and a pawl carried by said carriage, a movable jaw loosely engaging between said extensions and having an elongated opening parallel with said guide, a pin extending through said opening and fixed to said extensions, a handle, spaced apart cam members secured to said handle and engaging on opposite sides of said carriage, means pivotally securing said cam members to said carriage, a pair of spaced apart arcuate ribs carried by each cam member, and a pair of arcuate ribs carried by said movable jaw one on each side thereof eccentric to said pivot means and engaging between said ribs.

CLARENCE A. HUNTLEY.
